United States Patent Office

Des. 189,160
Patented Nov. 1, 1960

189,160

RADIO CABINET

John W. Mason, 1110 Huber Lane, Glenview, Ill.

Filed Aug. 20, 1958, Ser. No. 52,302

Term of patent 3½ years

(Cl. D56—4)

Fig.1

Fig.2

Fig. 3

Fig. 1 is a front perspective view of a Radio Cabinet, showing my new design;

Fig. 2 is an end elevational view thereof; and

Fig. 3 is an enlarged rear view thereof.

The dominant features of my design reside in the portions shown by full lines.

I claim:

The ornamental design for a radio cabinet, as shown and described.
